UNITED STATES PATENT OFFICE.

WILLIAM ROBERTS, OF BARBERTON, OHIO, ASSIGNOR TO THE DIAMOND MATCH COMPANY, OF CHICAGO, ILLINOIS, A CORPORATION OF ILLINOIS.

MACHINE FOR ASSEMBLING MATCH-BOOKS, &c.

1,218,000.

Specification of Letters Patent.

Patented Mar. 6, 1917.

Application filed April 1, 1916. Serial No. 88,824.

To all whom it may concern:

Be it known that I, WILLIAM ROBERTS, a citizen of the United States, and resident of Barberton, in the county of Summit and State of Ohio, have invented certain new and useful Improvements in Machines for Assembling Match-Books, &c., of which the following is a specification.

This invention relates to that class of machines whereby book matches and similarly shaped articles are assembled side by side with the corresponding ends of the contiguous articles in opposite relation to each other. The invention is more particularly an improvement on the oscillatory article positioning-mechanism set out in Letters Patent of the United States No. 1,132,268, dated March 16, 1915, which mechanism is therein illustrated as associated with a match-book making machine of the character described in Patent No. 1,042,472, dated October 29, 1912. In the machine of the latter patent match-books, wedge-like or tapering in form (owing to the match heads 25 of the covered cards or splints) are discharged from an intermittently rotatable turret element in succeeding pairs with the larger ends of the books rearward; and in the machine of the first mentioned patent 30 the said positioning mechanism is mounted and operated in such relation to the turret element as to receive the succeeding pairs of books and endwise reverse the pairs in alternation.

The object of the present invention is to provide an article positioning structure which is intermittently rotatable in one direction, instead of oscillatory as in the mechanism of Patent No. 1,132,268 referred to, thereby permitting the direct gearing of such structure with the turret element of the book-making machine in such a manner as to insure the smooth and timely operation of the positioning structure in relation to the said element.

Accordingly, my invention comprises, in a machine for assembling book matches and the like, a rotary positioning structure having an open article-receiving passage extending diametrically therethrough and having also, independently of said passage, radial pockets which open at the periphery of the structure, said passage and pockets being non-communicable and being arranged 55 in spaced relation to each other so that in

the intermittent rotation of the structure they are periodically positioned to receive match-books from the source of supply and transport the contained books successively to positions for vertical discharge from said structure with the heads or larger ends of the succeeding books arranged in opposite endwise relation to each other. 60

The invention also comprises features of construction and combinations of parts which will be hereinafter described and claimed. 65

In the drawings—

Figure 1 is a side elevation of a book-positioning structure and associated mechanism embodying my invention; the adjacent end of the trough or receptacle within which the books are assembled being shown in section. 70

Fig. 2 is a plan of Fig. 1. 75

Fig. 3 is a plan of the receiving end of the trough and the plunger head therein.

Fig. 4 is a transverse vertical section through the book-positioning member; as on the line 4—4 of Fig. 2. 80

Referring to the book-match machine, which, in the present instance, constitutes the source of book supply for the assembling apparatus, 10 designates an intermittently rotatable pocketed wheel, or turret, from which the finished book matches (α) are discharged in pairs, larger or headed ends rearward, upon a yielding supporting plate 11 by the action of the ejecting arms 12 of a reciprocating frame 13. 14 designates reciprocal fingers by means of which the free ends of the cover flaps of the books are tucked under the stapled end folds of the covers. When the tucking operation has been completed and the fingers leave the finished books, the latter are simultaneously pushed rearwardly, abreast, by the next succeeding pair of books, and so on. 95

15 designates a rotary book-positioning structure embodying my invention. This structure comprises a cylindrical body carried by a central stud shaft 16 having its bearing in a suitably-disposed supporting bracket 17. Fast on the stud shaft is a gear wheel 18 in mesh with an idler 19 which in turn meshes with a gear wheel 20 on the shaft 21 of the pocketed wheel of the book-match machine, whereby the structure 15 is intermittently rotated in the same direction as the pocketed wheel; the ratio of the co- 100 105 110

acting gears being such that in each movement of the turret 10 the positioning structure is advanced a quarter turn. The body 15 is provided with radial pockets 22 diametrically opposite to each other, and also with a passage way 23 extending diametrically through the body at right angles to the pockets, as seen most clearly in Fig. 4. In the present instance the body is of sufficient length to provide two corresponding alining pockets on each side thereof, and also two alining through passage ways at right angles to said pockets in order to accommodate the pairs of book-matches successively ejected from the turret 10 and imposed on the supporting plate 11 of the book-making machine, as seen in Fig. 2.

The structure 15 is mounted to rotate with its periphery adjacent the supporting plate 20 so that the pockets and passage ways are successively presented to the path of the books on said plate. Hence the consecutive pairs of books as they are pushed from the plate are received by the opposing pockets 25 or passage ways of the positioning structure and bodily transported thereby. The books contained in the pockets are maintained therein until the rotary structure makes three quarter-turns, in which case the pockets containing the books occupy a position vertically below the axis of rotation of the structure, whereupon such books, narrow ends downward, drop from the pockets; but the books contained in the 35 through passages remain therein only during one quarter turn of the rotary structure, in which case the passages being in vertical position permit the contained books to gravitate freely therefrom, larger ends downward.

A segmental guard plate 24 is arranged adjacent the outer peripheral surface of the rotary structure, so as to prevent the accidental egress of the books from the pockets 45 and passage way before they reach the vertical discharging position. This plate is conveniently supported on an underlying horizontal trough 25 into which the successive pairs of match books are delivered by the positioning structure. It is to be noted that in each rotation of this structure the open ends of the through passage way are positioned to receive the book-matches in alternation with the oppositely-disposed 55 pockets; and hence the succeeding pairs of books are discharged from the positioning structure into the trough in reversed positions as to their ends. Arranged within the trough is a plunger head 26 which is connected by means of a rod 27 with a depending bracket arm 28 on the reciprocating

frame 18, whereby in each forward stroke of the latter to eject a pair of match books from the turret 10, the plunger head is moved against the opposing match-books 65 to advance them along the trough.

The receiving portion of the trough is provided longitudinally thereof with suitably-spaced spring strips 29 which afford two parallel chambers of appropriate width 70 for the two rows of match books as they are progressively advanced by the plungers. These strips are spaced sufficiently to bear against the opposing edges of the articles and maintain them in upright position. The 75 ends of the strips adjacent the plunger are beveled and yieldable laterally, as at 30, so as to act in conjunction with the plunger as vertical guides for the articles as they are delivered to the trough, and yet permit the 80 advancement of the articles by the plunger.

I claim—

1. In a machine for assembling book-matches and the like, a rotary article positioning member having an article receiving 85 passage extending diametrically therethrough and having also independent radial article receiving pockets in spaced relation to said passage.

2. In a machine for assembling book-90 matches and the like, the combination with a receptacle, of means for delivering articles thereto with their corresponding ends in opposite relation to each other, said means comprising a rotary member having radial 95 pockets diametrically opposite to but separated from each other, and having also a longitudinal passage extending diametrically through said member in a plane at right angles to the said pockets, means for rotating said member, and means for progressively introducing articles to said pockets and to the respective ends of the passage.

3. In a machine for assembling book-105 matches and the like, the combination with an intermittently rotatable turret and means for ejecting articles therefrom, of a rotary article positioning member arranged to receive the articles ejected from the turret, 110 and gearing between said turret and positioning member whereby the latter is rotated in one direction only, said member comprising a body having an article receiving passage extending diametrically therethrough, 115 and having also independent radial article receiving pockets in spaced relation to said passage.

Signed at Barberville in the county of Summit and State of Ohio this 30th day of 120 March A. D. 1916.

WILLIAM ROBERTS.
